Alfred B. Ely.

United States Patent Office.

ALFRED B. ELY, OF NEWTON, MASSACHUSETTS.

Letters Patent No. 61,410, dated January 22, 1867.

IMPROVED MACHINE FOR CUTTING FILES.

The Schedule referred to in these Letters Patent and making part of the same.

TO WHOM IT MAY CONCERN:

Be it known that I, ALFRED B. ELY, of Newton, in the State of Massachusetts, have invented certain new and useful Improvements in Machinery for Cutting Files, of which the following, with the accompanying drawings, is an accurate description.

Figure 1 is a top view of the tool stock and adjuncts.

Figure 2 is a vertical sectional view of tool stock and arm.

In the cutting of files by hand the shank of the tool is surrounded by the elastic cushion of skin and flesh, and in striking the blow, sufficient play is given to the tool to produce the peculiar cut and tooth necessary for a good file. Again, the chisel, by means of the articulations of the joints, is made to conform to the surface of the file blank, and also to any required angle of the cut to the blank. Again, the tool is held at the end of a spring-arm. It is the design of my invention to meet these contingencies.

A is the tool stock. B is the chisel, its shank passing up through the stock. C is a lining of rubber within the stock encasing the shank of the chisel. This lining may be made of leather, preparations of rubber, or any suitable elastic substance. The tool is separate from the hammer, and the chisel slips up and down in the stock, and a strip or strips of metal may intervene between the elastic lining and the shank to prevent abrasion. A pin, a, through the shank above the rubber, or a nut, will keep the chisel in place, and the elasticity of the rubber will, when the chisel is struck, act as a spring to bring it back again, while shoulders below will prevent its being driven up into the stock. D is the arm of the tool stock, having a ball, E, at its end. F F are two ledges of metal on the rear of the tool stock, hollowed on their inner sides to form a socket for the ball E, the whole forming a ball and socket-joint, and enabling the tool to be turned in any direction and at any angle. Ordinarily it is only necessary that the tool shall turn laterally to the right and left to cut the proper cross-angle of tooth row, and vertically to the right and left to conform to the surface of the blank. G G are spring-bars pivoted above and below the ledges F F, at H, and bent down and up so as to press upon and clasp the arm D, at I I. If it be desired to prevent or limit the direct vertical (up-and-down) movement of the stock on the ball E, the bars I I, or either of them, may be made rigid, in which case it will form a ball and socket limited as to its motions in some directions. The outer edges of the ledges F are made circular, and may be graduated. The bar G, being pivoted at H, or at or near the centre of the tool stock, the stock may be moved either way, and confined at any point on the arc by a clamp-screw, K. In this way the tool edge may be set and held at any angle across the file blank. By means of similar ledges and bars and clamps on the sides, the tool may be set at any inclination over the file blank. A presser-foot or adjuster may be attached to the arm and so constructed and arranged as to conform to the surface of the file blank, and also to preserve its parallelism to the chisel, and also to be placed at such distance to and from the chisel as may be found desirable. The end of the arm D is a spring, L, attached to a rock-shaft, or pivoted or made fast at M. The whole arm may be constructed as a spring. The arm may be pivoted or jointed so as to move laterally near the rock-shaft, and turn adversely, as the tool-stock is turned, and allow the file to be cut without changing the position of the blank from the centre of the bed; the hammer-arm may be similarly constructed.

Having thus described my invention, what I claim in file-cutting machinery, is—

1. Lining the socket and grasping the tool in the stock or head with rubber, when the parts are arranged and constructed and operate substantially as and for the purposes described.
2. Connecting the tool holder or head with the arm or shaft, substantially as described.
3. The spring-arm D, in combination with the rubber-lined head, substantially as described.
4. The arrangement of the bars G, with the head and arm, substantially as and for the purposes described.
5. Regulating the angle of the cutting edge of the tool to the arm or shaft by means of bars and clamps, substantially as described.
6. The combination of the rubber-lined socket with the vertically swivelling head, substantially as described.
7. The combination of the rubber-lined socket with the vertically swivelling and horizontally turning head, substantially as described.

In testimony whereof I have hereunto subscribed my name.

ALFRED B. ELY.
